UNITED STATES PATENT OFFICE.

EDWARD F. CRANE, OF NEWARK, NEW JERSEY, ASSIGNOR TO H. A. CRANE & BRO., INC.,
OF JERSEY CITY, NEW JERSEY, A CORPORATION OF NEW JERSEY.

CONCRETE FLOOR CONSTRUCTION.

1,160,384.

Specification of Letters Patent.

Patented Nov. 16, 1915.

Application filed April 11, 1913. Serial No. 760,371.

To all whom it may concern:

Be it known that I, EDWARD F. CRANE, citizen of the United States, and resident of Newark, in the county of Essex and State 5 of New Jersey, have invented certain new and useful Improvements in Concrete Floor Construction, of which the following is a specification.

This invention relates to improvements in 10 floor construction, and more particularly to hollow floor construction comprising reinforced concrete and hollow forms distributed in spaced relationship within the floor. In a prior application filed by me January 15, 1911, Serial No. 601,558, there is illustrated one type of such hollow floor construction in which the forms are hollow blocks made in part of metal and in part of non-metallic elements, the construction 20 there illustrated being designed as to substitute for and improvement upon the old type of hollow concrete floor construction having terra-cotta or similar tiles or blocks distributed throughout the body of the concrete flooring. In both of the types of floor construction just referred to the forms, tiles or blocks are arranged on a flooring of false work in proper relation with one another with metallic reinforcing rods in position 25 between the rows, the floor being formed by pouring concrete in the usual manner among and around the forms, rods, etc., to fill all the intervening space and form a net-work of intersecting beams or girders joined by 30 the concrete to form a unitary reinforced concrete floor construction. In another application filed by me July 17, 1912, Serial No. 708,947, I have illustrated an improved floor construction in which tiles or blocks 35 formed wholly or in part of terra-cotta or other non-metallic material are dispensed with and the blocks used to form the hollow spaces in the flooring are merely forms, that is, means for providing hollow spaces in the 40 finished flooring, these forms being so made as to interlock with the poured concrete and also combine with suitable reinforcing means, in such a manner as to permit the formation of a complete finished reinforced 45 concrete floor with a smooth under side or ceiling surface, by merely pouring the concrete upon and around the forms and reinforcing means supported upon the false-work.

The present invention is an improvement

upon those just described, and particularly upon the invention described in the second of said cases. One of its essential elements is the provision of forms for making hollow spaces in the finished flooring, but these forms differ in many respects from those of said prior application, and are combined with other elements of the floor construction in a different manner. In this case the hollow forms used are mounted on supporting 60 means constructed as elements separate and distinct from the forms themselves, there being preferably a large number of supporting devices, each adapted to coöperate with a plurality of forms. The supporting 65 means is intended to rest upon false-work, but the hollow forms themselves will be elevated above the supporting surface of the false-work, and before the forms are placed in position the concrete may be 70 poured to form a continuous layer of concrete of the proper thickness at the under side of the floor construction, after which the forms will be placed in position on the supporting means and the remainder of the 75 concrete poured. The supporting means employed may be of any suitable type, but will preferably consist of a plurality of skeleton devices, each having pointed feet 80 adapted to rest upon the false-work in order 85 that the under side of the concrete when poured and set may present a finished ceiling surface unmarred by projecting metallic elements of the floor. The supporting devices employed in the present case are 90 substantially H-shaped skeleton supports or chairs, each adapted to receive and position one corner of the bottom edge of each of four hollow forms; and each supporting device is also preferably so constructed as to 95 support one or more reinforcing elements or bars of a metallic reinforcing layer. In general the construction is such that the hollow forms are mounted on and located side- 100 wise by supporting means by which the forms are elevated above the surface of the false-work on which the concrete reinforced 105 flooring is to be formed, and a reinforcing layer is mechanically supported in such a position above said level of the false-work that when the concrete is all poured and the floor finished the reinforcing layer will be firmly embedded in the concrete and at a level considerably above that of the finished ceiling surface.

Other features of my invention not hereinbefore referred to will be hereinafter described and claimed and are illustrated in the accompanying drawings, in which.

- 5 Figure 1 is a plan of a group of hollow forms mounted upon suitable supporting means constructed in accordance with my invention, and also combined with a metallic reinforcing layer mechanically sustained by
10 said supporting means, and illustrates the manner in which these parts are assembled on false-work before concrete is poured over them; Fig. 2 is a transverse section taken in line 2—2, Fig. 1, of a finished floor embodying the elements just described and also additional reinforcing means which will hereinafter be referred to; Fig. 3 is an enlarged perspective view of one of the supporting devices and a plurality of hollow
15 forms mounted on it, and also showing the manner in which reinforcing elements are sustained by and secured to said supporting devices, and Fig. 4 is an enlarged transverse section, similar to Fig. 2, of a portion of
20 said floor construction showing the relation of the parts after the first layer of concrete has been poured and before the pouring of the remainder of the concrete used in the floor construction.
25 Similar characters designate like parts in all the figures of the drawings.

As in the second of my aforesaid prior applications, the present floor construction is one in which hollow forms are completely
30 inclosed in poured concrete. The forms employed for the purpose are in their main features preferably similar to those described in the aforesaid application. Usually each form will be made of sheet metal,
35 for convenience and cheapness of construction, shipment, handling, etc., the construction illustrated being one in which the forms taper slightly in such a manner that a large number of them may be nested for
40 shipment so as to occupy but a small space. Each should of course be of sufficient strength to withstand the pressure of wet or green concrete during pouring, and each
45 also preferably should be strong enough to constitute in and of itself a reinforcing or stiffening medium in a finished floor. As here shown, each form is a hollow, tapering, box-like element of sheet metal, designated generally by *b*, having a dome-shaped top, *c*, and sides that are preferably corrugated or fluted, as shown at *d*, in order to increase
50 the resistance opposed by the side walls to loads borne by the finished flooring, and in order also to prevent movement of the forms
55 in the concrete when the latter has set. Each form is a hollow box substantially rectangular in horizontal section, closed at the top but entirely open at the bottom and preferably formed up from a single sheet of metal.

One of the principal features that distinguish the present invention from the construction of my aforesaid prior application disclosing the use of metallic forms is the provision of separate supporting means for elevating each form *b* above the level of false-work, such as *f*, on which the reinforced floor is to be formed. This separate supporting means is so constructed as to permit a layer of concrete to be poured before the forms are laid, after which the forms may be placed in position and the remainder of the concrete poured to obtain a floor construction in which, when the flooring is finished and the concrete has set, a relatively thick layer of concrete lies below each form and is connected or integral with the superimposed concrete of the floor construction to constitute a unitary floor presenting not only finished faces of poured concrete throughout its whole external surface, but also relatively thick walls of concrete at every point in its external surface. The specific supporting means employed herein is not only separate from the forms themselves but is so constructed that each element of it is adapted to receive and support a plurality of hollow forms. The construction illustrated is one in which a skeleton supporting device, designated generally by *s*, has, at
90 different horizontal levels, surfaces of small area adapted to rest upon the false-work, and other surfaces upon which the forms themselves are adapted to rest. The skeleton supports *s* shown have legs, 2, which
95 preferably terminate in points in order to reduce to the minimum the metallic surface in the plane of the ceiling surface of the finished floor construction. As shown, the skeleton support *s* is a substantially H-shaped member or chair, made up in this case of two substantially U-shaped sheet-metal elements secured together, as by rivets 3. The sides and cross-piece of each support are thus formed by simply stamping out and properly bending up sheet-metal elements, which are then connected together. The legs 2 are each bent substantially into the vertical plane of the diagonal of a square, in order to coöperate better with the hollow forms they are intended to receive and support. At the upper side thereof each of these legs is shown as having a stamped-out portion or opening, designated generally by 4, the bottom wall 5, of which constitutes the immediate supporting surface for a form. The length of each of these openings 4 is such as to permit the supporting devices and the forms to be readily assembled over the whole surface of the false-work, in the manner shown particularly in Figs. 1 and 3, without binding of the parts, a slight allowance of this sort having been found desirable in practice in
100 order to prevent delay in the assembling of
105

elements that may not always exactly fit. It will be noticed that each leg 2 has an upward extension, indicated at 2', which is adapted to enter an adjacent corner of a form *b* and locate the same in place. This extension is at the upper end of that portion of the leg 2 which is bent into line with the diagonal of a square (the square of the form) as before described.

- 10 The manner in which the forms and their supporting devices are combined, it is believed, will be obvious from the drawings. The supporting elements *s* are laid upon the false-work in rows with the separate supporting devices spaced substantially at the desired distances apart, and after the first layer of concrete has been poured the forms *b* are laid on said supporting devices, each corner of a single supporting device serving 20 to support one corner of each of four different forms, or, stated in other words, each corner of each form is carried by legs of four different supporting devices. When in place the lower edge of each box-like form 25 will rest at one corner upon a supporting surface 5 of an element *s*, and each form will be elevated above the false-work a distance corresponding to the height of the surface 5 above said false-work. It will be noted 30 that when the forms are seated on the supports, each individual support will coöperate with four adjacent corners of four separate forms. For this reason, the form seats are arranged in quadrangular relation when the 35 type of form illustrated in the drawings is employed.

The parts just described are sufficient for the purpose of forming with concrete, when the concrete is poured to the proper level, a 40 floor construction having hollow dome-shaped spaces substantially throughout the body thereof. In addition, however, suitable provision is usually and preferably made for reinforcing this construction. In 45 order to provide for such reinforcement, the supporting means before described will preferably be so constructed as to sustain a reinforcing layer made up, for example, of reinforcing bars or rods. In the construction 50 illustrated two crossing sets of metal reinforcing bars, each made up of parallel elements, are illustrated as mounted on, or supported by, the elements *s*. Here each of these elements is cut out, as shown at 6, to 55 form a supporting groove or seat in which a reinforcing bar of one set may be located, as will be obvious by referring particularly to Figs. 3 and 4. The bars of this set, indicated at 7, lie in the spaces between the rows 60 of forms *b* and resting directly upon the supporting elements *s* are permanently sustained by them, at the desirel level above the pointed ends of the legs 2. The bars of the other set are indicated at 8 and lie in the 65 other spaces between the forms *b*, being

shown as resting on top of the bars or rods 7 and tied thereto, as by tie-wires 9. To assure the central location of each rod 8 the cross-bar of each supporting device *s* may have a central nick, such as 10, in the under 70 side thereof through which the tie-wires 9 may pass. The net-work of crossing bars thus formed is at such an elevation above the level of the false-work as to permit the use of a reinforcing layer of sheet metal, 75 such as the usual wire netting 11, in addition to the reinforcing bars or rods. As shown in Fig. 4, this wire netting will usually lie close up against the under sides of the main portions of the side pieces and cross-bars of 80 the elements *s*, being connected thereto in any suitable manner, as, for example, by being tied at suitable intervals to said supporting devices by tie-wires 11'.

When the metallic parts are in the positions just described, it will be evident that the forms, their supports, are all of the reinforcing elements are positively located in the desired relation to the false-work, and that the reinforcing rods and netting are 85 held in fixed and permanent mechanical relation, which relation is determined before the pouring of the concrete. When so combined the desired reinforcement may be obtained in any given horizontal plane (within 90 limits) above the level of the false-work, that is, above the level of what is to be the finished ceiling surface.

In forming concrete reinforced flooring of the kind shown and described herein, the 100 wire netting is first unrolled and spread out on the upper surface of the false-work *f*. Then the supports or chairs *s*, properly spaced, may be placed in position in rows and on them are laid the crossing bars of 105 the main reinforcing layer. These bars are secured in position, as by tie-wires, in the manner before described, and the wire-netting is also properly elevated and secured in place, also by tie-wires. Concrete is then 110 poured over these parts until it reaches about the level of the surfaces 5 of the sides of the supports or chairs *s*, this level being indicated in Fig. 4, after which the forms are placed in position on the supports and may, 115 if so desired, be locked in connection with them by bending the lower edges of the forms at the corners thereof into under-cut notches 15 in the vertical arms or extensions 2' of the supports, as indicated by dotted lines in Fig. 4. In the event of the concrete 120 being poured to a depth above the openings 4 in the supports prior to the placing in position of the forms, the upward extensions 2' of the supports serve as a means to permit of the ready positioning of the forms in proper relation with said supports. After the forms have been placed in position as described the floor is then finished by pouring 125 the remainder of the concrete so as to cover 130

the reinforcing means and fill all the spaces around the metallic elements and between the forms up to the desired level, indicated in Fig. 2. When the floor is finished and the concrete has hardened, the floor construction will be a hollow reinforced floor with dome-shaped spaces therein near the tread or floor surface, 12, while the lower surface or ceiling surface, 14, will be a continuous one backed up by a relatively thick layer of concrete and completely inclosing all of the forms, supports and reinforcing elements previously described.

What I claim is:—

15 1. In a hollow floor construction involving the use of hollow forms, a form support provided with a plurality of recesses constituting seats in which the lower edges of separate forms are adapted to engage, said 20 supporting means being provided with extensions adjacent the recesses adapted to project upwardly into the interior of said forms, and each of said extensions being provided with a recess into which the lower 25 edge of the form may be bent to lock the form in place.

2. A skeleton form supporting device for hollow floor construction, comprising a substantially H-shaped frame and a plurality 30 of supporting legs depending below the plane of the under side thereof to support the same in elevated position, said H-shaped frame having a plurality of form supporting surfaces arranged at the extremities 35 thereof.

3. A skeleton form supporting device for hollow floor construction involving the use of hollow forms, comprising a body portion, a plurality of supporting legs depending below the plane of the under side thereof to support the same in elevated position, said 40 body portion having a plurality of form

supporting seats arranged in quadrangular relation and provided adjacent said form supporting seats with projections entering the hollow forms at the corners thereof to limit sidewise movement of the forms. 45

4. A form supporting device for hollow floor construction comprising two substantially U-shaped strips of sheet metal united to form a substantially H-shaped frame, said H-shaped frame having form seats at the extremities thereof, each adapted to support a portion of a form. 50

5. A form supporting device for hollow floor construction comprising two substantially U-shaped strips of sheet metal united to form a substantially H-shaped frame, and means to support said frame so that the arms thereof will lie in a horizontal plane. 55

6. A form supporting device for hollow floor construction comprising a skeleton frame having four upwardly projecting portions arranged in quadrangular relation and four downwardly projecting portions substantially in line with said upwardly projecting portions and serving as legs to support the frame in elevated position, and a form seat located adjacent each upward extension. 60

7. In a hollow floor construction, the combination with a form support provided with four form seats arranged in quadrangular relation, of four separate forms, each of the four adjacent corners of the forms being supported by one of said form seats. 65

Signed at New York, in the county of New York, and State of New York, this ninth day of April, A. D. 1913.

EDWARD F. CRANE.
